UNITED STATES PATENT OFFICE

2,441,796

DISCHARGE LAMP CIRCUIT

John H. Campbell, Altamont, N. Y., assignor to
General Electric Company, a corporation of
New York

Application October 23, 1945, Serial No. 623,937

5 Claims. (Cl. 315—99)

1

This invention relates to electric discharge devices and their circuits, and especially to the leading power-factor units of two-lamp lead and lag circuits. An important aim of the invention is to assure adequate current for preheating the cathodes of lamps in leading circuits before the arc discharge is initiated between the cathodes, and particularly cathodes embodying heating means through which the preheat current passes. The invention is hereinafter explained with particular reference to fluorescent lamps of the ordinary low pressure positive column electric discharge type.

In usual practice, a fluorescent lamp such as here referred to is connected across an A. C. operating or "discharge" circuit that includes inductive ballast for controlling and regulating the discharge current during operation. A starting circuit is connected across the operating circuit in parallel with the discharge gap between the electrodes, through their heating means aforementioned, and includes a starting switch (manual or automatic) by which the starting circuit is suddenly interrupted after current flow therein has brought the electrodes to a temperature of adequate thermionic emission. Owing to the inductive ballast in the operating circuit, this sudden opening of the starting circuit results in a high voltage kick between the electrodes, which usually suffices to initiate the discharge.

During the cathode-preheating period before initiation of the discharge, the inductive ballast in the operating circuit naturally tends to keep down the preheating current in the starting circuit. In the case of a leading power factor circuit—which includes a capacitor or condenser in series with the inductive ballast aforementioned, the pre-heating current under these conditions is little if any greater than the discharge current after starting, and does not suffice to preheat the cathodes quickly and adequately. It is therefore usual in such cases to include an inductive choke coil or "compensator" in the starting circuit in series with its switch, to coat with the inductive ballast and the capacitor of the operating circuit in bringing the combined circuit into at least partial resonance, and thus give a greater preheating current.

My invention allows of dispensing with such

10 a compensator in the starting circuit without any comparable addition to the system, thus simplifying it and reducing its cost.

The single figure of the drawing is a diagram 5 of lamp circuit arrangements embodying the invention.

The drawing shows a low pressure positive column discharge lamp 1 consisting of an envelope tube equipped with widely spaced cooperating electrodes 2, 2 in its opposite ends. Either or 15 each of the electrodes 2, 2 may be a thermionic activated cathode embodying an electric heater for bringing it to a temperature of electron emission before the discharge between the electrodes 15 is initiated. For instance, the electrodes 2, 2 may consist of tungsten filament wires, in coil or coiled coil form, charged or coated with activating alkaline earth oxides, such as a mixture including barium and strontium oxides. The envelope 1 20 may contain an atmosphere of gas or vapor or both at low pressure: e. g., an inert rare starting gas, like argon at 2 to 6 mm. of mercury, and a supply of mercury that is indicated by a droplet 3. Also, an internal coating of luminescent 25 material or phosphor 4 excitable by the radiation from the discharge is indicated on the envelope wall.

As shown, the electrodes 2, 2 are connected to 30 opposite sides of a discharge or operating circuit 5 which may be the leading branch of a two-lamp lead and lag circuit (the other branch of which is not shown), and includes the inductive ballast or reactor 6 and the capacitor 7 in series 35 with one another and with the discharge device 1, as is usual in such lead circuits. The discharge circuit 5 may be energized from any suitable source, such as a 110 to 120 volt 60 cycle A. C. lighting circuit, not shown. A manual control switch 8 is also shown, for controlling 40 energization of the circuit 5. A starting circuit 9 is shown connected across the discharge circuit 5 in parallel with the lamp 1, between and through the cathode coils or resistance heaters 2, 2, with a starting switch 10 therein. This switch 10 may be of any usual or preferred manual or automatic type, its function being to 45 suddenly interrupt the circuit 9 after the current through the coils 2, 2 has heated up the cathodes to a temperature of adequate electron emission.

thus producing a voltage kick across the lamp 1 which starts the discharge.

In accordance with my invention, a capacitor 11 is connected into one side of the discharge circuit 5 in shunt with reactive ballast represented by the choke 6, but in series with the lamp 1 and capacitor 7. The inductance 6 and capacitor 11 form a loop circuit whose resonance frequency depends (other things being equal) on the value of the current in the discharge circuit 5. The reactor or inductance 6 and the series capacitor 7 are chosen on the basis of giving a suitable or optimum current through the cathode coils 2, 2 for preheating the cathodes quickly and adequately before the arc discharge between these electrodes is initiated, but without regard to the wattage that they would by themselves give in the lamp 1 during ordinary operation. The reactor 6 is so chosen or designed that its reactive characteristic with varying current is non-linear. The capacitor 11 is so chosen that it does not materially affect the preheating current that flows while the starting switch 10 is closed, so that the cathodes 2, 2 heat rapidly, permitting a relatively prompt, quick start of the lamp 1 after the discharge circuit 5 is energized. During lamp operation, on the other hand, when the much greater resistance or impedance of the discharge path in the device 1 is substituted across the discharge circuit 5, the current in the circuit is lower than during starting. This is brought about by a decrease in saturation of the choke 6, which in combination with the capacitor 11 presents a higher effective impedance than during starting. The loop circuit including them is then closer to resonance. Hence the discharge current and the lamp wattage are kept down to the desired normal operating values at the line voltage center.

For the convenience of those wishing to use my invention, I give illustrative values of circuit constants suitable for an ordinary commercial 30 watt positive column fluorescent lamp of usual 36 inch tube length and 1 inch diameter; but these are not to be understood as defining or limiting the invention in its broader aspects. For example, the inductance 6 may be wound to give a 118 volt drop on a 60-cycle A. C. current of .34 amp. R. M. S., with a D. C. resistance of 7 ohms; and the capacitors 7 and 11 may have capacities of 4 mfd. and $\frac{1}{4}$ mfd. respectively. The cathode coils 2, 2 of the lamp 1 are assumed to be of the usual coiled coils of the 30 watt lamp above mentioned, each comprising an active length of 252 mm. of 2.85 mil diameter tungsten wire. For a supply voltage of 118 across the line or operating circuit 5, the cathode preheating current before starting will be 0.48 amp., against an operating voltage of 0.34 amp. after starting.

It will be understood that the values of circuit constants given are illustrative, and that even the circuits shown can be varied in some particulars, such as the portion of the operating circuit 5 shunted by the capacitor 11. E. g., this capacitor 11 might shunt only part of the inductance or reactive ballast 6.

What I claim as new and desire to secure by Letters Patent of the United States is:

1. For an electric discharge device having thermionic electrode means including electric heating means and a starting circuit connected to said heating means and across the gap between said electrode means, a leading power-factor operating circuit connected to said electrode and heating means including capacitance and reactive ballast of non-linear reactive char-

acteristic with current in series with one another, a starting switch connected across said discharge device and means for reducing the current transmitted to said discharge device after opening said switch upon initiation of a discharge within said device including capacitance in parallel with reactive ballast aforesaid to constitute therewith a parallel circuit approaching resonance.

2. In combination, an electric discharge device having thermionic electrode means including electric heating means, a leading power factor operating circuit connected to said electrode and heating means and including capacitance and reactive ballast of non-linear reactive characteristic with current in series with one another, a starting circuit including an interrupting switch connected to said heating means and across the electrode means, the impedance of said ballast being substantially smaller when said switch is closed than when open, and means for limiting the current transmitted to said discharge device to a value less than that which would be established by the increased impedance of said ballast incident to reduced current flow occasioned by opening said switch comprising a capacitor connected across said ballast and constituting therewith a parallel circuit approaching resonance.

3. In combination, an alternating current circuit, an electric discharge device comprising a pair of electrodes at least one of which is of the thermionic type, a starting switch connected across said electrodes, a serially connected capacitor and a non-linear inductive ballast connected between one terminal of said circuit and one of said electrodes, said ballast having a relatively small impedance during a starting operation wherein substantial starting current is transmitted through the thermionic electrode upon closure of said switch, the other electrode being connected to the other terminal of said circuit, and a second capacitor connected in parallel with said inductive ballast and having a capacitance which with the inductance of said ballast, after initiation of a discharge between said electrodes and after opening said switch, constitutes a circuit tuned to approach the frequency of said circuit in order to limit the current supplied to the discharge device during operating conditions.

4. In combination, an alternating current supply circuit, an electric discharge device having a pair of thermionic electrodes each provided with heating means, a leading power-factor circuit connected between one terminal of said supply circuit and one of said heating means and comprising a serially connected capacitor and a non-linear inductive ballast, a starting switch connected directly across said electrodes and which upon closure effects the transmission of heating current in series relation through the heating means for said pair of electrodes, and means for controlling the current transmitted to said discharge device after initiation of a discharge between said electrodes and after opening said switch and comprising a capacitance connected across said ballast to constitute therewith a parallel circuit approaching resonance to limit the current transmitted during normal operating conditions.

5. In combination, an alternating current supply circuit, an electric discharge device having a pair of thermionic electrodes of the filamentary type, a leading power-factor circuit including a serially connected inductive ballast and a capacitor connected between one terminal of said supply circuit and one of said electrodes, means com-

prising a starting switch connected across said electrodes for effecting transmission of starting current from said supply circuit through said electrodes and said ballast and capacitor, and means for reducing the current transmitted to said discharge device upon initiation of a discharge between said electrodes and after opening said switch comprising a capacitor connected across said ballast to constitute therewith a parallel circuit approaching resonance.
